Inventor

STEPHEN HENRY EMMENS,

By John S. Gurn,

Attorney

UNITED STATES PATENT OFFICE.

STEPHEN H. EMMENS, OF LONDON, ENGLAND.

PROJECTILE.

SPECIFICATION forming part of Letters Patent No. 414,388, dated November 5, 1889.

Application filed October 22, 1888. Serial No. 288,768. (No model.)

To all whom it may concern:

Be it known that I, STEPHEN HENRY EMMENS, a subject of the Queen of Great Britain and Ireland, and a resident of London, England, temporarily residing at Harrison, in the State of New York, have invented a new and useful Improvement in Projectiles, of which the following is a specification.

This invention relates to externally-applied 10 thimble-shaped projectiles for guns.

It consists in certain novel features of construction and combinations of parts hereinafter set forth and claimed, whereby such projectiles are primarily adapted to serve as 15 grapnels, with or without provision for opening the arms by the grapnel-line after the projectile drops, and with or without provision in the shape of sharpened rear edges for cutting torpedo-lines and the like; also, to be 20 readily converted into parachutes for carrying pyrotechnic lights and the like, and, finally, to be readily converted at will into my load-carrying projectile, which constitutes in part the 25 subject-matter of a companion case, Serial No. 288,766, filed October 22, 1888.

A sheet of drawings accompanies this specification as part thereof.

Figure 1 of these drawings is a side view, half in elevation and half in section, of the 30 projectile proper with grapnel-arms attached. Fig. 2 is a rear end view of the same. Fig. 2^x represents alternative cross-sections of the grapnel-arms. Fig. 2^z is a perspective view of the two parts of the removable pivot 35 of one of the grapnel-arms. Fig. 3 is a small-scale side view of a suitable gun for throwing the projectile, showing in dotted lines the projectile as above thereon. Fig. 4 is a like view of the same projectile, representing it as 40 landed or dropped, and illustrating by full and dotted lines the operation of opening the arms. Fig. 5 is a like view of the same projectile, represented as fired with its arms open. Figs. 6 and 7 are like views of the same projectile converted into a parachute pyrotechnic 45 device, representing the same respectively as ascending and descending.

Like letters of reference indicate corresponding parts in the several figures.

The projectile proper comprises a metallic 50 guide-tube A, closed in front by a head B, and open at the rear to admit the barrel or powder-

tube A', Fig. 3, of the gun from which it is fired. It is provided at or near its rear end with three (or more) outwardly-projecting 55 vanes or "wings" C for regulating its flight, and with a swiveled eye or loop D at bottom, which may conveniently be attached by means of a collar D², fitted to the rear end of the 60 tube A, as shown.

At its head end the projectile is provided with an eye or loop E in front, and with two or more side eyes or loops F. The loops F are preferably double and four in number, as shown, so as to serve for the attachment of 65 four folding grapnel-arms G or G², removably pivoted to the same, as hereinafter set forth. In front of their pivots g the arms G are preferably extended forward at a suitable angle, and terminate in eyes i, from which four 70 strong cords k, Fig. 4, may extend in pairs through said front loop E from opposite sides thereof to the grapnel-line, (represented at L,) which in this case extends rearward through said loop D at the rear end of the projectile, 75 and is free to run through the latter, so that a strong pull thereon may open the arms, as represented in Fig. 4; or, if preferred, the arms G may be preliminarily fastened open by means of a cord or wire m, Fig. 5, passing 80 through the eyes i, and in this case the grapnel-line would be attached to said loop D, as represented at L², Fig. 5. If the grapnel is to be used for cutting torpedo-lines in rivers and harbors, or for a like purpose, the arms 85 would be made of hardened steel with sharpened rear edges, as represented at G², Fig. 2^x. For other purposes arms having blunt rear edges, as represented at G, Fig. 2^z, would be preferable. In all cases the front ends of the 90 arms G or G² are more or less sharp, and in the parachute species of the convertible projectile, which is represented by Figs. 6 and 7, and is selected for my specific claims, these sharp ends of the arms G or G² occupy eyelets h at the corners of a parachute-cover H, of a suitable flexible fabric. The center of the cover H is provided with an opening, through 95 which the front end of the projectile proper is passed, and the edges of which are provided with eyelets h², from which straining-cords j extend to the front loop E of the projectile. 100 A cup I, containing a suitable pyrotechnic-light compound and fuse, is conveniently sus-

pended in inverted position from the loop D at the rear end of the projectile, and the whole is now ready to be fired from the gun. Its flight is represented by Fig. 6, and its slow descent, with the cup I lighted, is represented by Fig. 7. A highly-efficient device for nocturnal illuminations is thus readily formed.

To provide for readily and quickly converting the projectile into other forms, as hereinbefore stated, the pivots g , Figs. 1 and 2 ^{a} , of the arms G (or G^2) are made removable, as represented by the figure last named, and are fastened in place by screws g^2 , tapped into the respective arms radial to their pivot-holes. The ends of the pivots occupy the bores of the double lugs F, and by turning back the screws the pivots may be easily removed and the arms detached.

The gun represented by Fig. 3 comprises a short powder-tube A', a breech-block B', a firing-device tube C', a stock-tube D', and a stock E', and is represented as provided with horizontal trunnions F' and pivoted in a vertical swivel G', to facilitate holding and aiming it with one of my said projectiles thereon. This gun constitutes in part the subject-matter of another companion case, Serial No. 288,767, filed October 22, 1888, and forms no part of my present invention.

Another suitable gun for throwing my said projectiles is set forth in a previous specification, forming part of my allowed application for United States patent, filed June 14, 1888, Serial No. 277,098.

I do not claim herein a thimble-shaped projectile provided externally with wings for regulating its flight and with loops to which interchangeable attachments may be coupled. This is claimed in the companion case, Serial No. 288,766, hereinbefore referred to. Neither do I claim, broadly, the combination, with a projectile, of pivoted grapnel-arms with or without a cover applied thereto, nor guiding-wings, as I am aware that such combinations, broadly considered, have before been effected in grapnels, drag-anchors, and projectiles of other descriptions.

In combination with a suitable gun, as hereinbefore set forth, my improved projectile is adapted to carry and is provided at 50 once with rigidly-projecting wings of effective area, and with grapnel-arms, which may be fastened open and fired, thus effectively spread, or provided with a light parachute-cover of any suitable flexible fabric, as they 55 do not enter the gun.

Having thus described my said improvement in projectiles, I claim as my invention and desire to patent under this specification—

1. A thimble-shaped projectile comprising a guide-tube open at the rear and having a head which closes its front end, and provided with rigidly-projecting guide-wings and with 60 grapnel-arms in front of said wings, substantially as hereinbefore specified.

2. A thimble-shaped projectile comprising a guide-tube open at the rear and provided with a head which closes its front end, and with rigidly-projecting guide-wings and folding 70 grapnel-arms, the latter located in front of said wings and having removable transverse pivots, substantially as hereinbefore specified.

3. A thimble-shaped projectile comprising 75 a guide-tube open at the rear and provided with a head which closes its front end, rigidly-projecting guide-wings, folding grapnel-arms located in front of said wings, and an eyeleted parachute-cover of a flexible fabric 80 applied to said arms, substantially as hereinbefore specified.

4. A thimble-shaped projectile-body provided externally with double lugs at or near its head end, in combination with removable 85 pivots fitted to said lugs, and grapnel-arms fitted to the same and provided with locking-screws, substantially as hereinbefore specified.

STEPHEN H. EMMENS.
